CLAIM

The ornamental design for a vehicle mirror, as shown and described.

DESCRIPTION

FIG. 1 is a front, left perspective view of a left vehicle mirror showing our new design;

FIG. 2 is a front, right perspective view thereof;

FIG. 3 is a front view thereof;

FIG. 4 is a left side view thereof;

FIG. 5 is a right side view thereof;

FIG. 6 is a top view thereof;

FIG. 7 is an enlarged view of the claim as shown in FIG. 1 with environment removed for clarity purposes;

FIG. 8 is a front, right perspective view of a right vehicle mirror showing our new design, which is a mirror image of the vehicle mirror of FIGS. 1-7;

FIG. 9 is a front, left perspective view thereof;

FIG. 10 is a front view thereof;

FIG. 11 is a right side view thereof;

FIG. 12 is a left side view thereof;

FIG. 13 is a top view thereof; and,

FIG. 14 is an enlarged view of the claim as shown in FIG. 8 with environment removed for clarity purposes.

The uneven-length broken lines immediately adjacent to the shaded area define the bounds of the claimed design and form no part thereof. The even-length broken lines depict the remainder of the vehicle mirror and form no part of the claimed design.

1 Claim, 14 Drawing Sheets
